BALER

Stanley D. Russell, Racine, Wis., assignor to J. I. Case Company, Racine, Wis., a corporation

Application October 23, 1943, Serial No. 507,359

2 Claims. (Cl. 100—23)

1

The present invention relates to balers and particularly to compressing devices for the chambers thereof and is similar to the compressor shown in the application of Russell, Serial No. 389,396, filed April 19, 1941, now Patent No. 2,362,861, issued November 14, 1944, of which this application is a continuation in part.

An object of the invention is to generally improve the construction and operation of machines of this class.

A further object is to provide improved means for compressing the outlet end of a bale chamber.

Further objects and advantages of the invention will be apparent from the following specification and accompanying drawing in which a satisfactory embodiment of the invention is shown, but it is to be understood that the invention is not limited to the details disclosed but includes all such variations and modifications as fall within the spirit of the invention as herein expressed.

In the drawing,

Figure 1 is a left side elevation of so much of a baler as necessary to illustrate the invention.

Fig. 2 is a plan view of the same.

Fig. 3 is a vertical sectional view on the line 3—3 of Fig. 1.

Referring to Fig. 1, the baler to which the invention applies includes a chamber generally designated as 10 of the type disclosed in applicant's above identified application including side members or plates 11 and upper and lower members 12 and 13 between which is reciprocable a compressing plunger 14. Fibrous material is fed into the chamber in any suitable or well-known manner not necessary to illustrate and is compressed and forced backwardly between members 12 and 13, material previously compressed engaging frictionally the members 12 and 13 and forming an abutment against which further material is compressed by plunger 14.

Under different conditions, it is desirable to vary the intensity of this frictional engagement and for this purpose it is common to compress the rear or right end of the baling chamber. For this purpose a compressor unit generally designated as 15 is used and placed on chamber 10.

Member 12 in the present instance comprises a plate 16 having angle irons 17 and 18 united therewith by rivets or the like 19—19. Angle irons 17 and 18 therefore provide down-turned flanges at the edges of plate 16. In similar manner member 13 comprises a plate 20 having angle irons 21 and 22 united therewith by rivets or the like 23—23.

2

Member 13 carries an extension generally designated as 24 and comprising a plate 25 having downwardly turned edge flanges 26 and 27 (in one position of the extension), said plate being provided with ears 28 and 29 pivotally connected by bolts 30 and 31 with above mentioned angle irons 21 and 22 respectively. Extension 24 has two positions, an elevated or inoperative position shown in full lines in Figs. 1 and 2 and a lowered or operative position shown in dot-dash lines in Fig. 1. In the latter position, extension 24 acts as a shelf over which bales may be discharged. Owing to the smooth character of the upper surface of extension 24, in its lowered position, bales 15 may slide easily over the extension without confinement and under certain conditions may be discharged otherwise than straight back in line with the baler.

An abutment 31a is provided on extension 24 and contacts any convenient portion of the underside of member 13 to determine the position or attitude of extension 24 in its lowered position.

Compressor unit 15 comprises upper and lower elements 32 and 33 respectively extending across the width of the baling chamber in contact with members 12 and 13. Members 32 and 33 are urged toward each other by tension rods 34 and 35.

Member 32 in the present instance comprises an angle iron having a vertical flange 36 and a horizontal flange 37 whereas member 33 comprises an angle iron having a vertical flange 38 and a horizontal flange 39. Tension rods 34 and 35 pass through suitable apertures in horizontal flanges 37 and 39 and have heads 40 and 41 in the present instance engaging flange 39. Springs 42 and 43 are positioned respectively on tension rods 34 and 35 above flange 37 and compressed between it are hand nuts 44 and 45. The compression of springs 42 and 43 is thus transmitted to members 12 and 13 thereby tending to compress the end of bale chamber 10. The degree of compression may be determined by adjusting nuts 44 and 45 to give the required pressure in springs 42 and 43.

Owing to the differences in frictional characteristics of different materials which may be baled in chamber 10 and for other reasons, it becomes desirable to compress chamber 10 at different points in its length for different materials. In the present instance, above mentioned flange 37 is provided with apertures 46 of such size and disposition that they may fit over rivet heads 19. Also, in like manner flange 39 is provided with apertures 47 so positioned that they 55 may fit over above mentioned rivet heads 23.

When in place on chamber 10, engagement of the flanges 37 and 39 with the rivets as aforesaid, prevents displacement of compressor 15 on chamber 10, the rivets serving as detents for preventing accidental displacement of compressor 15, but the latter may be readily shifted to various points along chamber 10 by sufficiently loosening nuts 44 and 45. Under these conditions, members 32 and 33 may be readily disengaged from rivets 19 and 23 and compressor 15 shifted to a new location. Retightening of nuts 44 and 45 of course locks the compressor in the new position. Compressor 15 may be engaged with members 12 and 13 at points between rivets 19-19 and 23-23, if desired, but without the advantage of the detent effect of the rivets.

In the present instance a tool box generally designated as 48 and having a cover 49 is attached to flange 36 as by bolt 50.

The above being a complete description of an illustrative embodiment of the invention, what is claimed as new and desired to be secured by Letters Patent of the United States is:

1. In a baler, a baling chamber including op-

posed wall portions, at least one of which is composed of a plurality of elements, rivets uniting said elements at spaced points and providing a plurality of spaced exposed head portions, and means applied to the baling chamber for compressing the same and having openings engageable with said exposed head portions to be maintained by said rivets in any one of a plurality of desired positions to exert a compressing pressure thereon in different places for different conditions of operation.

2. In a baler, a baling chamber including opposed wall portions adapted to be compressed for retarding the passage of baled material there-through, means applied to the baling chamber for compressing it, said means engageable with said chamber at different places to exert compressing pressure thereon at a plurality of positions for different conditions of operation, and interengaging detent means on said chamber and compressing means for maintaining the latter in any one of said plurality of positions.

STANLEY D. RUSSELL.
